Primary Examiner — Karen E Kearney*Assistant Examiner* — John M Otte(74) Attorney, Agent, or Firm — Michael Best & Friedrich LLP(57) CLAIM

We claim the ornamental design for a display screen including a graphical user interface, as shown and described.

DESCRIPTION

The sole FIGURE is a front view of a display screen including a graphical user interface of the design.

Portions of the graphical user interface shown in broken lines form no part of the claimed design.
